[57] CLAIM

The ornamental design for a handsaw, as shown and described.

DESCRIPTION

FIG. 1 is a left side elevational view of a handsaw showing my new design;
FIG. 2 is a bottom plan view thereof;
FIG. 3 is a right side elevational view thereof;
FIG. 4 is a top plan view thereof;
FIG. 5 is an end elevational view thereof;
FIG. 6 is an opposite end elevational view thereof;
FIG. 7 is a left side elevational view of the second embodiment of FIG. 1 thereof;
FIG. 8 is a bottom plan view of the second embodiment thereof;
FIG. 9 is a right side elevational view of the second embodiment thereof;
FIG. 10 is top plan view of a second embodiment thereof; and
FIG. 11 is an end elevational view of the second embodiment, the opposite end being a mirror image thereof.
